UNITED STATES PATENT OFFICE

98,582

DESIGN FOR A COMBINED ICE CRUSHER AND BEVERAGE CONTAINER

Thomas J. Fegley, Jenkintown, and George O. Leopold, Philadelphia, Pa., assignors to North Bros' Mfg Co., Philadelphia, Pa., a corporation of Pennsylvania

Application June 22, 1935, Serial No. 57,372

Term of patent 7 years

To all whom it may concern:

Be it known that we, Thomas J. Fegley and George O. Leopold, citizens of the United States, residing, respectively, in Jenkintown, Montgomery County, Pennsylvania, and Philadelphia, Philadelphia County, Pennsylvania, have invented a new, original, and ornamental Design for a Combined Ice Crusher and Beverage Container, of which the following is a specification, reference being had to the accompanying drawing, forming part thereof, in which:

Figure 1 is an elevational view of the combined

ice crusher and beverage container showing our design; and

Fig. 2 is a top plan view thereof.

The body portion of the container is transparent.

We claim:

The ornamental design for a combined ice crusher and beverage container, substantially as shown and described.

THOMAS J. FEGLEY.
GEORGE O. LEOPOLD.
